CLAIM

The ornamental design for a swimsuit, as shown and described.

DESCRIPTION

FIG. 1 is a front view of a swimsuit showing my new design; FIG. 2 is a rear view thereof; FIG. 3 is a left side view thereof; and, FIG. 4 is a right side view thereof.

The broken lines illustrating a model are for environmental purposes only and form no part of the claimed design. The broken lines illustrating portions of the swimsuit form no part of the claimed design. The dot-dash broken lines define the bounds of the claimed design and form no part thereof.
